UNITED STATES PATENT OFFICE.

LEE W. BLEIER, OF NEW YORK, N. Y.

CUTTING-MACHINE.

1,306,327.

Specification of Letters Patent. Patented June 10, 1919.

Application filed September 15, 1916. Serial No. 120,244.

To all whom it may concern:

Be it known that I, LEE W. BLEIER, a citizen of the United States, residing in the borough of Manhattan, city, county, and State of New York, have invented a certain new and useful Improvement in Cutting-Machines, of which the following is a specification, reference being had to the accompanying drawings, which form a part of the same.

An object of my invention is to provide a machine adapted to cut commodities, yeast for instance, in predetermined lengths which may be fed therein in continuous streams or otherwise.

Another object of my invention is to provide a machine adapted to cut off a section of such commodity with the downward stroke of the cutting element and another section of the commodity with the upward stroke of the cutting element.

Another object of my invention is to cut said commodity perpendicularly while the same is in continuous motion, the cutting element traveling with the commodity at the same forward speed as said commodity during the cutting operation.

Another object of my invention is to bring back the cutting element after each cutting stroke to such position that upon each successive cutting stroke the material will be cut perpendicularly.

Another object of my invention is to provide means for setting in motion the cutting element by the action of the traveling commodity upon a lever which it engages and then immediately accelerating the further movement of said lever out of the path of said commodity.

Another object of my invention is to regulate the size and weight of the cut sections.

Other objects will be apparent in this specification and the accompanying drawings.

Referring now to the drawings,

Figure 1 is a plan view looking down on the machine from the top.

Fig. 2 is a side elevation taken along the line B—B of Fig. 1, partly in section and partly in dotted outline.

Fig. 3 is a cross sectional view taken along the line a—a of Fig. 2 looking in the direction of the arrow.

Fig. 4 is a cross-section taken along the line E—E of Fig. 2, looking in the direction of the arrow.

Fig. 5 is an end elevation of the machine partly in cross-section.

Fig. 6 is an inside elevation looking in the direction from the near side of Fig. 1, the near frame of the machine having been removed.

Fig. 7 is an elevation from the opposite side of the machine of Fig. 6 showing the near side frame in the background, and

Figs. 8 and 9 are side elevations with the frame removed partly in cross-section and partly in dotted lines showing the platform, cam and Geneva wheel operations.

This application is a companion application to application for patent of Lee W. Bleier, Serial Number 120245 carrier machines, filed September 15, 1916. The carrier machine application referred to fully describes the method of discharging the cut commodity from the machine of the present application and while the carrier machine is illustrated generally at the left of Fig. 1 of the drawings accompanying this specification, still it is unnecessary to describe the construction and operation thereof, as this carrier machine constitutes no part of the invention sought to be protected hereby.

Referring now in detail to the drawings in which the same reference characters refer to the same parts throughout, 1 and 1^A represent the frame of the machine. Mounted in this frame is the main driving shaft 53 on which are splined and travel therewith the sprocket wheel 46 and the ratchet wheel 12. The sprocket wheel 46 engages the chain 80 which in turn engages the sprocket wheel 47. This sprocket wheel 47 is splined to the pulley shaft 75 carried in the frame of the machine, on which is mounted and travels therewith the pulley wheel 49, carrying the belt C.

In Fig. 7 the ratchet wheel 12 is shown out of engagement with the pawl 11 carried by the pawl disk 13. This pawl 11 when not influenced by the locking lever 9 acting on the pawl lever 10 is spring-pressed into operative position with the ratchet wheel 12, and travels with said ratchet wheel, carrying with it the pawl disk 13 which is suitably mounted for that purpose. In the position shown in Fig. 7 the ratchet wheel is traveling idly with the main driving shaft 53. The pawl disk 13 is carried on the main sleeve 51 of the main driving shaft 53, and is subjected to operation by the releasing of the pawl 11 on the pawl disk 13 and the engage-

ment thereof with the ratchet wheel 12. Extending between the main driving shaft 53 and the main sleeve 51 is a stationary sleeve 52 on which is keyed the arm 45 which is held rigid with the frame of the machine by the pin 45', which extends through the said arm 45 at one end and at the other end through the frame of the machine, and holds the sleeve 52 stationary. Mounted on the sleeve 51 and adapted to travel therewith are the Geneva arm 14 and the gear wheel 44. This Geneva arm is provided with a roller 95 which is adapted to successively engage the scallops 81 of the Geneva wheel 15, thus giving the said wheel intermittent movements of one-quarter turn each. The Geneva wheel 15 is mounted on and operates a counter shaft 54, on the other end of which is splined the gear wheel 16 which imparts an intermittent movement to the gear wheel 17 which is one-half the peripheral circumference of its intermeshing gear 16. This gear wheel 17 is mounted on the shaft 59 and is provided with a crank 17' pivotally linked with the stud 36 through the pivot 70 and link 35. The stud 36 has securely bolted to it the slide 37 mounted on which is the bracket 34 supporting the shaft 64 in the bearing 82. On this shaft are splined standards 31 and 32 at the opposite ends of which are mounting means 41 and 41' for the cutting element 42, here illustrated as wire, and adjustment means in the form of a tension screw 40. As will be hereafter explained this cutting element is given an arc movement, being a combination of an up and down movement in which direction it cuts and a horizontal movement to compensate for the moving of the commodity subjected to the cutting operation.

For the purpose of guiding the cutting element in its perpendicular movements there is provided a shoulder stud 33 on the standard 31, which shoulder stud operates in the guide path H controlled by the slide 2.

The slide 2 is adapted to slide horizontally and for that purpose is mounted in bearings 83. This slide 2 in its operation is controlled by lever 29 mounted on shaft 76 which also has splined thereto the depending arm 62 which in turn is pivotally linked with the pawl 7. A pin A projects from the lever 62 extending over the end of the slide 2 and engages the same so as to return the said slide to the original position through the operation of said depending arm 62 by the pawl 7. This pawl rests on the pin 84 which projects from the frame of the machine, and in operation the pawl engages the pin 8 which projects from the slide 2. The locking lever 9 is forked at one end so as to engage with and be controlled by the pin 8. The other end of this lever is adapted to engage with pawl lever 10 and hold the same in such position as to prevent the pawl

11 from engaging with the ratchet wheel 12. This pawl lever 10 is provided with a pin 100 which is adapted to ride over the pawl 11 when the said lever is released by the reciprocation of the pawl 7 thus throwing the end of the locking lever 9 out of contact with the pawl lever 10. Upon such condition happening the pawl 11 is spring-pressed into the ratchet wheel 12 and is carried therewith together with the pawl disk 75 13 and all of the members on the sleeve 51.

The lever 62 is connected to the frame of the machine by a spring 85, and the stud 36 is linked to the frame of the machine by the spring 86.

The cams 18 and 19 are splined on the sleeve 57. These cams are illustrated to show the line of travel of the rollers 69 and 68 respectively. In practice these cams are provided with races or guide paths for said rollers controlling the direction of travel of said rollers along the lines of the cams outlined. The roller 68 which is controlled by cam 19 is connected with and controls link 23 which is secured to the shaft 72 and rocks the same. Links 24, 24' are also secured to said shaft 72 and are rocked thereby and at the ends of said links 24, 24' are pivoted the platforms 27, 27' which platforms are also pivoted on to parallel levers 25, of which only one is shown but the arrangement corresponds to levers 24 and 24' which in turn are pivoted at 71 in the frame of the machine as shown. It will be seen that the rocking of the shaft 72 will give the platforms 27, 27' an arcuate movement. Between these platforms 27, 27' the carrier belt C is adapted to travel and the said platforms are so arranged as to lower commodities which have been cut into predetermined lengths onto the traveling belt and be carried thereby.

The roller 69 which is controlled by the cam 18 is connected with the link 21 which with the link 22 is pivoted to the frame of the machine at 65, and the said link 22 is pivotally linked to the lever 28 through the link 26 as shown. This lever 28 in turn is splined on the shaft 76. At the end of the link 21 is a pin 60 which projects into the path of the lever 22 effecting an operative contact between the links 21 and 22 so that link 22 is limited in its movement with reference to link 21. Pin 80 is connected with slide 2 and operates in slot S in the frame of the machine and limits the reciprocal movement of slide 2. The lever 29 is secured in operative position on shaft 76 by the screw 87. It will be seen that lever 29 may be adjusted in any position on said shaft and then clamped thereto by the set screw 87.

As has been said the Geneva arm 14 is carried on the sleeve 51. This Geneva arm engages the Geneva wheel mounted on the shaft 54, through the coöperation of the

roller 95 with the scallops 81, giving the Geneva wheel an intermittent motion. As shown, this Geneva wheel makes one complete revolution to four revolutions made by the Geneva arm. As will be seen the operation of the Geneva arm 14 is controlled by the coöperation of the pawl 11 with the ratchet wheel 12 so that when the pawl is out of engagement with the ratchet wheel 12, the Geneva arm 14, the Geneva wheel 15 and the parts operated therethrough are stationary. On the same shaft 54 with the Geneva wheel 15, and adapted to rotate with said shaft, is a gear wheel 16, located on the outer side of frame member 1^a. This gear wheel engages the pinion 17 mounted on the shaft 59 which is adapted to rotate therewith. The pinion 17 (Fig. 4) is provided with an arm 17', which is connected by the shoulder screw 70 to the link 35 and which in turn is connected at its other end to the shoulder stud 36, the inner side of which stud 36 is secured to the slide 37. The operation of the gear wheel 16 (Fig. 7) upon the pinion 17 gives the arm 17' a crank movement and the stud 36 a reciprocal movement in the slot 36'. A spring 86 is secured at one end in the frame of the machine and at the other end to the stud 36. The gear wheel 16 bears the ratio of one to two with the pinion 17 so that upon one revolution of the gear wheel 16 the pinion 17 performs two revolutions. Upon the Geneva arm roller 95 leaving its immediately previously engaged scallop 81, the counterbalancing spring 86 rapidly draws back into the position shown in Fig. 7 and Fig. 5, the stud 36 and all mechanism influenced by its movement. When in this position the Geneva wheel 15 has turned a quarter of a revolution and the Geneva arm roller 95 commences the engagement of another scallop 81 of the Geneva wheel 15.

The mode of operation of the machine is as follows: The machine may be driven from any suitable source, and in the drawings I have shown an electric motor 89 for this purpose. This motor is provided with a driving pinion 90 which gears with the gear wheel 91. Carried by this gear wheel 91 is a pinion 92 which meshes with the gear wheel 93 on the main driving shaft 53 of the machine. It will be seen that the gear 91 and pinion 92 are compensating elements in the transmission of power from the motor to main driving shaft 53. This main driving shaft operates directly the sprocket wheel 46 and the ratchet wheel 12 which are in continuous motion while the machine is in operation. The sprocket wheel 46 drives the sprocket chain 80 over another sprocket wheel 47 on the shaft 75, upon which is splined the pulley 49. Over this pulley, and controlled thereby, travels the carrier belt C which, being driven di-

rectly from the main driving shaft 53 is in continuous motion while the machine is being operated. The commodity to be cut is fed into the machine from any suitable source of supply as for instance nozzle 88, the longitudinal shape thereof being determined by the mouth of said nozzle. The commodity is fed through the nozzle 88 onto the bracket 6 which is supported on the standard 4. A second bracket 5 is shown supported on this same standard 4. These brackets 5 and 6 are provided with recesses E and F respectively, into which the cutting element 42 respectively retires after each stroke. The commodity is then fed onto the platforms 27 and 27', one of which is positioned on one side of carrier belt C and the other of which is positioned on the other side of carrier belt C. These platforms describe an arcuate path being carried below the said carrier belt C and depositing on said belt the section of commodity which has just been cut. Before this commodity is deposited on the carrier belt C and while the same is resting on the platforms 27 and 27' and traveling with said platforms, the said commodity presses against the lever 29 which is secured to shaft 76, and shifts said lever, rocking said shaft therewith. The lever 62 being also secured to said shaft 76 is also rocked, and carried therewith is the pawl 7 which connects with the pin 8 secured to the slide 2 and moves the said slide in the same direction as the moving commodity. The pin 84 stationed in the frame of the machine cooperates with the curved portion of the pawl or latch 7 to move this latch out of engagement with the pin 8 at or near the limit of its movement in order that the spring 85 when cam 18 permits may actuate the latch and lever 62 to return the lever 29 to its lowermost or operative position. The release of the latch 7 from engagement with the pin 8 is necessary in order that the further movement imparted to the lever 29 by the cam 18, levers 21, 22, etc., may take place while the slide is moving. The locking lever 9 being in engagement at its forked end with the pin 8 is swung out of contact with the pawl lever 10 and as a result the pin 100 connecting with said pawl lever 10 rides over the outer edge of pawl 11, thus unlocking the same, and being spring-pressed, this pawl falls into engagement with the continuously moving ratchet wheel 12 on the continuously moving main driving shaft 53. As a result the pawl 11 together with the pawl disk 13 which is splined to the sleeve 51 is given a rotating movement. The Geneva arm 14 which is also splined on the sleeve 51 is also given a rotating motion and the roller 95, which is connected to said Geneva arm 14, engages with one of the scallops 81 of the Geneva wheel 15.

wheel 15, moving this wheel one-quarter of a turn. As a result the movement of this Geneva wheel gives a quarter movement to the gear wheel 16 both of which wheels 5 are splined to the shaft 54. The gear wheel 16, having twice the peripheral circumference of the gear wheel 17, with which it meshes, gives the gear wheel 17 a one-half turn, to the quarter turn given to 10 the gear wheel 16, thus swinging the crank 17' to its opposite position and carrying with it the slide 37 and its attachments including the cutting element 42.

While this cutting operation is taking 15 place the cams 18 and 19 which are splined to the sleeve 57 are given motion from the sleeve 51 on the main driving shaft 53 through the gear wheel 44 meshing with and of the same size as the gear wheel 20, which 20 is also splined to the sleeve 57, said motion being controlled by the engagement of the pawl 11 with the ratchet wheel 12. The cam 19 controls the raising and lowering of the platforms 27, 27' above and below the 25 rapidly moving belt C, one of these platforms being on each side of the said belt. This motion is timed so that the platforms 27, 27' will lower the commodity onto the rapidly moving belt C as soon as it is cut by 30 the perpendicular movement of the cutting element 42. The platforms however are given a forward movement when in their upper position corresponding with the forward movement of the cutting element 42 35 so that while the commodity to be cut is on said platforms moving at a very much reduced speed from that of the carrier belt C, the cutting operation is taking place. As has been above pointed out the bracket 34 40 supports the standards for the cutting element 42 in such manner as to permit a rocking movement so as to effect a straight cut through the moving commodity subject to this operation. The cam 19 is also so 45 shaped that the platforms 27, 27' are given an arcuate movement about an imaginary axis. That is, these platforms are carried in the greater part of their travel when below the belt in a direction opposite to that of 50 its movement, and when above the belt in the direction of the movement thereof, but at a very much reduced rate of speed from that of the belt, the movement of these platforms being timed with the vertical movement of the cutting element 42.

Cam 18 which is also mounted on the sleeve 57 controls the speed of movement of the lever 29 through the links 21, 22 and 26 being so timed that when the commodity 60 has been cut off into its predetermined length the lever 29 will be accelerated in its movement out of contact with the commodity and raised high enough for the commodity to pass under and be rapidly moved away 65 by its contact with belt C upon the plat-

forms 27, 27' being lowered below the said belt. The operation of these cams is such that upon the commodity being cut off and passed out of the machine the parts of the machine are all returned to their initial position, except the cutting element 42 and its standards; the said cutting element being in a diametrically opposite position so that upon the further movement of the machine it will cut the commodity in the opposite direction from that of its last movement. That is, the cutting element is adapted to operate to cut off one length in its downward movement, and to cut off another length in its upward movement. 75

To recapitulate, the commodity is fed through the nozzle 88 onto the twin platforms 27 and 27' which are located at this time above the plane of the carrier belt C and circulate at each side thereof. The platforms move slowly as compared with the carrier belt C and with a movement which corresponds with the movement of the slide 2 so as to enable the cutting element, carried on the bracket 34 and its attachments to make a straight cut of the commodity. When the commodity has been cut, the platforms 27 and 27' in their circular movement fall below the rapidly moving belt C. Before this happens, however, the commodity engages lever 29 and presses the same forward and in the manner described through the latch 7, the pin 8 in the slide 2, and the locking lever 9 releases the pawl lever 10, throws the spring actuated pawl 11 into engagement with the ratchet wheel 12 mounted on the shaft 53. This action puts into operation the pawl disk 13 mounted on the sleeve 51 which carries with it the Geneva arm 14 and the gear wheel 44 which are also splined to the sleeve 51. The Geneva arm 14 engages the Geneva wheel 15 giving it one-quarter of a turn and the gear wheel 16 splined to the same shaft as the Geneva wheel 15 is given one-quarter of a turn and draws down the cutting element 44 to its lowermost position through the crank lever 17 which is given a half turn, the stud 36, the bracket 37 and the supports 31 and 32 for the cutting element. 90 100 105 While this action is taking place, the gear wheel 44 acts upon the gear wheel 20, splined to the sleeve 57 and rotates the cams 18 and 19 which are splined to the same sleeve 57. The cam 19 controls the circular action of the platforms 27 and 27' as described and the cam 18 moves the lower lever 29 away from the moving commodity through the levers 21, 22 and 26 until the downward path of said cam is brought into 115 contact with the roller 69 when the spring 85 returns these parts to their original position, through the action of pin A in lever 62, which extends over the slide 2 and engages the same. 120 125 130

While these parts just described are thus acting, the latch 7 draws the slide 2 so as to permit the cutting of the commodity by the wire 42 in a straight manner while the commodity is moving; the cutting element 42 moving with the commodity through the travel of the brackets 5 and 6 attached to the said slide 2. When the cutting element reaches the downward or upward position 10 the roller 69 on the cam 18 reaches the downward path of said cam and the counterbalancing spring 86 draws these parts back to the original position as shown in Fig. 7.

The depending lever 29 is adjustable on shaft 76 by set screw 87, and provides means for varying the length and weight of the commodity to be cut.

In the above description and the accompanying drawings I have shown the preferable embodiment of my invention but I do not wish to be confined to the disclosure therein contained but what I desire to cover by Letters Patent is set forth in the appended claims.

25 Claims:

1. In a cutting machine, a cutting element, standards for said cutting element, a supporting shaft suitably mounted to rockably support said cutting element and 30 its standards means for vertically reciprocating said standards and cutting element, means for rocking said cutting element and standards while in perpendicular motion, suitably supported brackets having grooves 35 between which said cutting element is adapted to reciprocate and retire in the said grooves, and means for returning said brackets to initial position after each cutting operation.

2. In a cutting machine, a cutting element, supports for said cutting element, a supporting shaft suitably mounted to rockably support said cutting element and its supports, means for vertically reciprocating 45 said supports and cutting element, and means for rocking said cutting element and supports while in perpendicular motion, suitably supported reciprocating brackets having grooves between which said cutting element is adapted to reciprocate and retire into said grooves, and means for returning 50 said brackets to initial position after each cutting operation, a carrier belt and means to operate the same, a platform on each side of said carrier belt, and means to circulate said platforms around the sides of said carrier belt above and below the plane thereof, said platforms moving in the same direction as said carrier belt when above the plane 55 thereof and partly in the same direction as said carrier belt when below the plane thereof.

3. In a cutting machine, a cutting element, supports for said cutting element, a 60 supporting shaft suitably mounted to rock-

ably support said cutting element and its supports, means for vertically reciprocating said supports and cutting element, and means for rocking said cutting element and supports while in perpendicular motion, 70 suitably supported reciprocating brackets having grooves between which said cutting element is adapted to reciprocate and retire into said grooves, and means for returning said brackets to initial position after each 75 cutting operation, a carrier belt and means to operate the same, a platform on each side of said carrier belt, and means to circulate said platforms around the sides of said carrier belt above and below the plane thereof, 80 said platforms moving in the same direction as said carrier belt when above the plane thereof and partly in the same direction as said carrier belt when below the plane thereof, a depending projection suitably supported in the path of and adapted 85 to be engaged by the commodity passing through the machine, and means operated by the engagement of said lever by said commodity to accelerate said lever out of 90 the path of said commodity.

4. In a cutting machine, a cutting element, standards for said cutting element, a supporting shaft for said standards, a journal in which said supporting shaft is rockably supported, a bracket to support said journal, guides for said bracket, a stud secured to said bracket, a crank arm, a link connecting said stud to said crank arm, a pinion adapted to operate said crank arm, 95 a gear to operate said pinion, a Geneva wheel, a shaft to which said gear and said Geneva wheel are keyed, and means for operating said gear wheel intermittently so as to turn said crank substantially one-half 100 a revolution, and a counterbalance for returning said crank and its controlled parts to initial position.

5. In a cutting machine, a cutting element, standards for said cutting element, a supporting shaft for said standards, a journal in which said supporting shaft is rockably supported, a bracket to support said journal, guides for said bracket, a stud secured to said bracket, a crank arm, a link connecting said stud to said crank arm, a pinion adapted to operate said crank arm, a gear adapted to operate said pinion a Geneva wheel, a shaft to which said gear and Geneva wheel are keyed, a pawl disk and means to rotate same, a Geneva arm adapted to engage said Geneva wheel, a sleeve to which said pawl disk and Geneva arm are keyed, said Geneva arm coöperating with said Geneva wheel to rotate said Geneva wheel intermittently so as to move said crank substantially one-half a revolution 110 and a counterbalance for returning said crank and its controlled parts to initial position.

6. In a cutting machine, a cutting element, standards for said cutting element, a supporting shaft for said standards, a journal in which said supporting shaft is rockably supported, a bracket to support said journal, guides for said bracket, a stud secured to said bracket, a crank arm, a link connecting said stud to said crank arm, a pinion adapted to operate said crank arm, a gear adapted to operate said pinion, a Geneva wheel, a shaft to which said gear and Geneva wheel are keyed, a pawl disk and means to rotate same, a Geneva arm adapted to engage said Geneva wheel, a sleeve to which said pawl disk and Geneva arm are keyed, said Geneva arm coöperating with said Geneva wheel to rotate said Geneva wheel intermittently so as to move said crank substantially one-half a revolution, a spring connected at one end in the frame of the machine and at the other with said stud adapted to be distended and released when said crank has described substantially one-half a revolution, the tension of said spring drawing back said stud and controlled parts to initial position. 65
7. In a cutting machine, a cutting element, standards for said cutting element, a supporting shaft for said standards, a journal in which said supporting shaft is rockably supported, a bracket to support said journal, guides for said bracket, a stud secured to said bracket, a crank arm, a link connecting said stud to said crank arm, a pinion adapted to operate said crank arm, a gear to operate said pinion, a Geneva wheel, a shaft to which said gear and said Geneva wheel are keyed, a pawl disk, a Geneva arm, a sleeve to which said pawl disk and Geneva arm are keyed, said Geneva arm being adapted to coöperate with said Geneva wheel and give it intermittent motion, a pawl mounted on said pawl disk, a ratchet wheel, said pawl being adapted to engage with and be released from said ratchet wheel, and a main driving shaft, said ratchet wheel being keyed to said main driving shaft. 70
8. In a cutting machine, a cutting element, standards for said cutting element, a supporting shaft for said standards, a journal in which said supporting shaft is rockably supported, a bracket to support said journal, guides for said bracket, a stud secured to said bracket, a crank arm, a link connecting said stud to said crank arm, a pinion adapted to operate said crank arm, a gear to operate said pinion, a Geneva wheel, a shaft to which said gear and said Geneva wheel are keyed, a pawl disk, a Geneva arm, a sleeve to which said pawl disk and Geneva arm are keyed, said Geneva arm being adapted to coöperate with said Geneva wheel and give it intermittent motion. 75
9. In a cutting machine, a cutting element assembly, comprising a cutting element, standards for said cutting element, a supporting shaft mounted to rockably support said cutting element and its standards, means for vertically reciprocating said cutting element assembly, a slide and mounting means therefor said slide being adapted to reciprocate horizontally, brackets having grooves mounted on said slide, said slide being provided with a vertical groove, coöperating means between the groove of said slide and the cutting element assembly so as to control the horizontal movement of said cutting element assembly in its vertical motion. 80
10. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 85
11. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 90
12. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 95
13. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 100
14. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 105
15. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 110
16. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 115
17. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 120
18. In a cutting machine, having a cutting element assembly comprising a cutting element, standards for said cutting element, and a supporting shaft suitably mounted to rockably support said cutting element and its standards, means for vertically reciprocating and for rocking said cutting element assembly, a carrier belt and means for operating the same, platforms on each side of said carrier belt and means for rotating said platforms above and below the plane of said carrier belt so that the motion of said platforms will be in the same direction of said carrier belt when above the plane thereof, and partly in the same direction as said carrier belt when below the plane thereof, a depending projection in the path of commodities adapted to be fed onto said platforms and to be engaged by said commodities. 125

ties, a shaft on which said depending projection is mounted, a lever, mounted on said shaft, a latch connected to said lever and adapted to be controlled thereby, a slide 5 suitably mounted to move horizontally and having a projection therefrom adapted to be engaged by said latch, means for moving said latch out of engagement with said projection, a locking lever controlled by said 10 projection, a pawl lever having a projection therefrom, a pawl disk and pawl mounted thereon, said pawl lever through its projection being adapted to control said pawl and said locking lever being adapted to control 15 said pawl lever, means for rotating said pawl disk, a sleeve to which said pawl disk is keyed, a gear on said sleeve, a second sleeve and gear and cams keyed thereto said gear being adapted to be controlled by the 20 gear on the first mentioned sleeve, links connecting one of said cams with the aforesaid depending projection extending into the pathway of the commodity, a shaft adapted to support said projection, a spring connected 25 at one end in the frame of the machine and at the other to the aforesaid second depending lever, the aforesaid cam being provided with an enlarged portion and a reduced portion, said spring being released 30 while the enlarged portion is acting and distended when the reduced portion is acting in which latter case the said spring draws back the second depending lever together with all parts controlled thereby to initial 35 position.

Copies of this patent may be obtained for five cents each, by addressing the "Commissioner of Patents, Washington, D. C."

11. In a cutting machine, having a cutting element assembly comprising a cutting element, standards for said cutting element, and a supporting shaft suitably mounted to rockably support said cutting element and 40 its standards, means for vertically reciprocating said cutting element assembly means for horizontally reciprocating said cutting element assembly simultaneously with its vertical movement, platforms adapted to receive 45 a commodity to be cut, carrier means to carry the commodity out of the machine, means to circulate the aforesaid platforms on either side of said carrier means above and below the plane of the same, in the direction of the movement of said carrier means when above the plane thereof, and partly in the same direction as said carrier belt when below the plane thereof, means to operate said carrier means, a projection extending 50 into the pathway of the commodity, a shaft adapted to support said projection and means to adjust the position of said projection on said shaft for the purpose of varying the length and weight of the commodity passing through the machine, and means to accelerate the said projection out of the path of said commodity upon the engagement of said commodity with said projection. 55
